SUCTION END-CATCHER IN RING SPINNING
AND TWISTING MACHINESChristian Just, Winterthur, Switzerland, assignor
to Actiengesellschaft Joh. Jacob Rieter & Cie., —
Winterthur, SwitzerlandApplication April 11, 1949, Serial No. 86,661
In Sweden April 19, 1948

7 Claims. (Cl. 57—34.5)

1

My present invention relates to the arrangement of auxiliary means for pneumatically sucking-off thread ends in ring frames and ring twisting frames.

In frames provided with such suction means, it has been customary to dispose portions thereof in a special box secured to the frame, which arrangement, however, requires excessive space and hinders the traffic in the mill rooms. When setting up in the mill new machines provided with such boxes, the additional space required therefor naturally reduces the number of spindles which can be accommodated in the room. Such additional structural units or annexes therefore are uneconomical, so much more as various parts already present in one frame-endwall are duplicated in the said box.

The said disadvantages are avoided by the arrangement according to the present invention in that the motor-driven suction fan and a filter are incorporated in one of the frame end shields which is formed as a box.

The space enclosed by the said end-shield suitably is divided by a filter and an apron wall supporting the suction fan into two compartments, and an air inlet is provided in the end-shield wall adjacent the machine, such inlet being co-axial with the said fan.

One form of my present invention is shown in the accompanying drawing, in which—

Fig. 1 shows the end portion of a spinning machine in elevation, the appurtenant end shield being illustrated in section, and

Fig. 2 is a corresponding partial view in which, however, the foot portion of the end shield has been swung open.

In Fig. 1, the roller beam 2 and spindle rail 3 are fixed to the main wall 1 of the end shield. An apron wall 4 provided in the upper portion of the end shield is spaced from the main wall 1 and extends over the entire width of the machine, as does a filter screen 5 which together with the apron wall 4 subdivides the space of the boxlike end shield in two chambers *a* and *b*. The electric drive motor 6 is flanged to the apron wall 4, and the fan wheel 7 is pinned to the overhung shaft end of motor 6. A suction port 8 is formed in the main wall 1 coaxially of the fan wheel 7 and opens towards the machine. A central suction header or collecting duct 9 opens into the suction port 8.

The filter or screen 5 is disposed in a swing structure 10 which is pivoted on pins 11 to the foot of main wall 1 so that it may be tilted away from the machine. A rod 12 traverses the cham-

2

ber *a* and is rockably mounted in the main wall 1, and a locking arm or detent 13 is pinned to each end of rod 12, outside the end shield. The said detents are engageable on studs 14 fixed to the small sides of structure 10 and project therefrom. Further, a swing gate 15 which extends over the entire width of the machine or chamber *a*, is pinned to said rod 12 so that, when disengaging the detents 13 from the studs 14 and swinging the same upwards to the position shown in Fig. 2, the gate 15 shuts the bottom opening in the upper portion of chamber *a*. The motor 6 disposed in chamber *b* projects through an opening in the wall 16 of the end shield into a hood 17 which has an open bottom. The fan wheel 7 is disposed in the upper portion of chamber *a*.

The fan 7 driven by motor 6 sucks air containing fibres and perhaps lengths of thread through the header 9 from the drawing means of the machine and moves the same in direction of the arrows shown towards the filter screen 5. The fibres and broken ends are retained on the screen 5 and in the chamber *a*, while the air traverses the screen 5 and the chamber *a* and flows to the outside partly through the hood 17 and partly through the openings of a screen 18. The fibres and thread ends, collected on the filter screen 5 have to be removed from time to time. For such purpose either of the detents 13 is swung manually from its locking position shown in Fig. 1 into the position shown in Fig. 2, the other detent 13 also being swung into such latter position through the axle rod 12. During such rocking movement, an extension 19 provided on each detent 13 is disengaged from the appurtenant stud 14 of the structure 10, which permits the latter to tilt to the position shown in Fig. 2, and the swing gate 15 is brought into abutment against the foot of the apron 4 whereby the air stream is prevented from entering the lower portion of chamber *a*.

The elements mounted as described on the machine for sucking-off broken ends require only little space, and the arrangement operates very economically owing to the aerodynamically favorable location of the suction blower and filter screen. By reason of the fact that the air-outlet hood surrounds the motor to a substantial amount, the motor is well cooled so as to permit to use a fully closed motor, which affords a high reliability of operation. Owing to the arrangement of the filter screen as described, the latter may be cleaned while the suction means are in

operation so that such cleaning does not disturb the spinning operation proper.

What I claim as new and desire to secure by Letters Patent is:

1. In a textile ring frame or ring twisting frame having an end shield formed as a hollow box-like structure, a motor-driven suction fan located in said box-like end shield, a filter screen located in the box-like structure in position to receive air from the fan and filter out broken thread ends which have been sucked away from the textile frame by the fan.

2. In a ring spinning or ring twisting frame having pneumatic suction means for broken threads, the combination with an end shield supporting longitudinally extending members of the frame, said end shield being formed by a box-like structure, of a partition wall within the end shield structure, a motor driven fan mounted on said partition wall, and a filter screen within said structure, said partition wall and said filter screen dividing said box-like structure into two chambers, said suction fan being arranged for delivering the drawn-in air stream into one of said chambers and forcing it across said filter screen into the other chamber, whereby broken threads and fibres are collected by said filter screen.

3. A ring spinning or ring twisting frame as claimed in claim 2 and comprising an electric motor driving said suction fan, said motor being carried by said partition wall on one side thereof and said suction fan being disposed on the other side of the partition wall.

4. In a ring spinning or ring twisting frame having pneumatic suction means for broken threads, the combination with an end shield supporting longitudinally extending members of the frame, said end shield being formed by a box-like structure, a partition wall within said structure to provide two chambers within the end shield, a filter screen forming part of said partition wall, a motor driven suction fan disposed in one of said chambers, an electric motor carried by said partition wall and disposed opposite said suction fan in the other chamber, the wall of said other chamber forming an outwardly open hood member surrounding said motor, whereby the stream of air delivered by said suction fan into said first mentioned chamber traverses said filter screen to pass into said other chamber and to be discharged therefrom through said open hood member.

5. In a ring spinning and ring twisting frame the combination with an end shield supporting longitudinally extending members of said frame, of an arrangement for pneumatically drawing off broken threads, said arrangement including a box-like end shield structure, a partition wall within said box-like structure to divide said structure into two chambers, a motor driven suction fan disposed in one of said chambers, an electric motor carried by said partition wall and

disposed in the other chamber, a filter compartment pivotally mounted in said end shield structure, a filter screen disposed in said filter compartment, said filter screen in normal position of the filter compartment forming an extension of said partition wall, whereby the stream of air delivered by said suction fan into said first mentioned chamber is forced to traverse said filter screen and to flow into said other chamber, a pivotally mounted closing gate adapted to interrupt communication between said first mentioned chamber and the filter compartment and locking means for holding the filter compartment in said normal position, said locking means being operatively connected to said closing gate, whereby upon release of said locking means to swing the filter compartment away from the end shield, said closing gate is actuated to close said first chamber and intercept the air stream delivered by said suction fan.

6. A ring spinning or ring twisting frame comprising an end shield supporting the ends of longitudinally extending members of the frame, said end shield forming a box-like structure, a substantially vertical partition wall depending from the top of said end shield, a filter screen extending from the lower edge of said partition wall towards the bottom of the end shield, said partition wall and filter screen vertically dividing the end shield in two chambers, a suction fan disposed in one of said chambers, a longitudinally extending suction line abutting at said chamber, an electric motor driving said suction fan, said motor being secured to said partition wall and disposed in the other of said chambers, and an air outlet in said other chamber in proximity to said motor, whereby the stream of air drawn by the fan through said suction conduit and delivered into said first mentioned chamber is forced through said filter screen into said second mentioned chamber and discharged towards said outlet.

7. In a ring spinning or ring twisting frame having pneumatic suction means for broken threads and fibres, the combination with an end shield supporting longitudinally extending members of the frame, said end shield being formed by a box-like structure provided with air inlet and outlet openings, a central suction collector for broken threads and fibres connected to said air inlet opening, a motor driven suction fan mounted within said box-like end shield structure to draw in air through said suction collector and expel the drawn in air through said outlet opening, and a filter screen disposed within said end shield structure in the path of air between said inlet and outlet openings whereby broken threads and fibres arriving with the suction air through said collector are separated from the air by said filter screen.
